UNITED STATES PATENT OFFICE

2,420,988

BOWLING BALL CLEANER AND POLISHER

Albert Henry Tholen, Clara City, Minn.

Application May 10, 1944, Serial No. 534,917

2 Claims. (Cl. 15—97)

1

This invention relates to new and useful improvements in cleaning and polishing spherical bodies and particularly bowling balls.

The principal object of the present invention is to provide a machine adapted to spin a ball in such a manner as to cause its entire surface to move against a polishing ring to thoroughly remove all grit and other foreign matter and desirably polish the surface of the ball.

Other objects and advantages of the invention will become apparent to the reader of the following description.

In the drawings:

Figure 1 is a side elevational view of the machine with the polishing ring shell in section.

Figure 2 is a top plan view of the machine with the shell broken away.

Figure 3 is a rear elevational view with the shell in section.

Figure 4 is an enlarged fragmentary vertical sectional view through the polishing ring.

Figure 5 is a side elevational view of a gear driven type machine with the polishing ring shell in section.

Figure 6 is a top plan view of the machine with the shell broken away.

Figure 7 is a rear elevational view of the form of the invention shown in Figure 5 with the shell in section.

Figure 8 is an enlarged fragmentary vertical sectional view through the polishing ring.

Referring to the drawings wherein like numerals designate like parts, it can be seen that Figures 1 through 4 illustrate one embodiment of the present invention and this consists of a stand including corner posts 5, supporting a top 6 and a lower platform 7 upon which an electric motor 8 is mounted.

Cross members 9 are located between certain corner posts 5 for supporting bearings 10 through which the ends of a shaft 11 are journaled.

On one end portion of the shaft 11 is a pulley 12 in vertically spaced relation to a smaller pulley 13 located on the armature shaft 14 of the motor 8 and a belt 15 is trained over these pulleys 12 and 13. In this manner the shaft 11 is driven by the motor 8.

A circumferentially concave rotor 16 is suitably secured to the shaft 11, the purpose of this rotor is to spin a bowling ball or the like A within a polishing ring generally referred to by numeral 17.

As can be seen in Figure 4, a channeled structure 18 forming part of the ring assembly 17 is located on the top 6 in circumscribing relation

2

to a circular opening 19 through which a ball A depends to rest upon the rotor 16.

Numerical 20 denotes a ring having a circumferential outside groove 21 for receiving a drive belt 22.

The ring 20 has a depending circumferential rib 23 which rests on roller bearings 24 located in the bottom of the channeled structure 18. Ball bearings 25 may be interposed between opposite sides of the channeled structure 18 and corresponding sides of the rib 23.

A polishing annulus 26 is affixed to the inside of the ring 20 and against this the ball A moves in the operation of cleaning and polishing the surface thereof.

A hood or shell 27 is secured by suitable members 28 to the top of the stand and this shell has a circular opening 29 therein through which a ball can be disposed to rest upon the rotor 16.

The belt 22 is disposed downwardly against the pair of pulleys 30 to pass under a pulley 31 located on the opposite end of the shaft 11 from the pulley 12.

Obviously, as the motor 8 drives the shaft 11 and the shaft 11, in turn, operates the rotor 16 for spinning the ball A and rotates the ring 20 for wiping the element 26 against the surface of the ball, a cleaning and polishing action will take place which in effect will thoroughly clean and polish a bowling ball in a short period of time.

A modification of the invention is shown in Figures 5 to 8, inclusive, and in this form of the invention a stand is provided and made up of a plurality of corner posts 32 supporting a top 33 and a platform 34 upon which a motor 35 is located. The motor 35 has a shaft 36 driving a pulley 37 which by a belt 38, in turn, drives a pulley 39 located on a shaft with a circumferentially concaved rotor 40 and a bevel gear 41.

The rotor 40 operates on a ball A in the same manner as before described, the ball operating within a ring 42 having a wiper lining or annulus 43. This ring 42 also has a depending rib 44 with roller bearings 45 and ball bearings 46 arranged in the same manner as in the first form of the invention, these bearing elements being located within a channeled structure 47 on the top 33.

The only difference in the ring 42 over the ring 20 of the first form of the invention is the provision of a ring gear 48 at its periphery instead of a belt groove.

A bracket 49 supporting a bearing 50 accommodates a vertical shaft 51 which has a gear 52 at its upper end meshing with the ring gear 48.

and a bevel gear 53 at its lower end meshing with the bevel gear 41. The operation of this machine is the same as the machine of the first form.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A ball cleaning and polishing device comprising a stand for supporting the ball, a ring mounted on top of the stand in horizontal position for receiving a ball placed therein and being 15 rotatable about its axis, a cleaning and polishing liner in said ring adapted to be rotated thereby about the ball in wiping engagement therewith, a ball spinning rotor, means to mount said rotor on the stand beneath the ring to support the ball 20 in said ring including a drive shaft for the rotor, a belt and pulley connection between said shaft and said ring whereby said shaft simultaneously rotates said ring and said rotor, and means for driving said shaft.

2. A ball cleaning and polishing device comprising a stand for supporting the ball provided

on top thereof with an annular channel structure, a cleaning and polishing ring surmounting said structure and adapted to receive a ball therein, means for rotatably mounting the ring comprising anti-friction bearings in the channel of said structure and a concentric annulus on said ring disposed in said channel and engaging said bearings, a rotatable ball spinning member against which the ball is adapted to rest and be spun in said ring mounted on said stand for rotation simultaneously with said ring, and means for rotating said ring and ball spinning member.

ALBERT HENRY THOLEN.
